US00D852836S

(12) **United States Design Patent** (10) **Patent No.:** **US D852,836 S**
Hofner et al. (45) **Date of Patent:** **** Jul. 2, 2019**

(54) **DISPLAY SCREEN WITH GRAPHICAL USER INTERFACE**

(71) Applicant: **Siemens Aktiengesellschaft**, Munich (DE)

(72) Inventors: **Matthias Hofner**, Hafenlohr (DE); **Judith Onodi-Wolff**, Heroldsberg (DE)

(73) Assignee: **Siemens Aktiengesellschaft**, Munich (DE)

(**) Term: **15 Years**

(21) Appl. No.: **29/648,649**

(22) Filed: **May 23, 2018**

(30) **Foreign Application Priority Data**

Nov. 24, 2017 (EM) 004520930

(51) **LOC (11) Cl.** **14-04**

(52) **U.S. Cl.**

(57) **CLAIM**

The ornamental design for a display screen with a graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE is a front elevational view of a display screen with graphical user interface showing our new design.

The broken lines illustrate a display screen and form no part of the claimed design.

1 Claim, 1 Drawing Sheet
(1 of 1 Drawing Sheet(s) Filed in Color)
